UNITED STATES PATENT OFFICE.

ISAAC S. CRAIG, OF SOMERVILLE, MASSACHUSETTS, ASSIGNOR TO ORPIN BROTHERS, OF BOSTON, MASSACHUSETTS.

MACHINE FOR LAYING REEDS.

SPECIFICATION forming part of Letters Patent No. 629,774, dated August 1, 1899.

Application filed March 8, 1899. Serial No. 707,840. (No model.)

To all whom it may concern:

Be it known that I, ISAAC S. CRAIG, a citizen of the United States, residing at Somerville, in the county of Middlesex and State of Massachusetts, have invented a new and useful improvement in machines for laying reeds in making roll-tops for desks and like rolls for other uses, consisting of strips of wood glued to flexible backs of canvas or other suitable materials, of which the following is a specification.

My invention relates to mechanism for "laying reeds," or, in other words, covering such flexible backs with a facing of wood glued thereto in the form of narrow strips or "reeds," so as to present a finished wooden surface, the completed product constituting a "roll" suitable for roll-top desks and for other purposes; and the object of my invention is to produce a machine capable of accurately and expeditiously laying reeds upon such glued flexible backs and to automatically clamp the same thereon successively during a progressive movement of said back to the extent desired, and I attain said object by the mechanism illustrated in the accompanying drawings, in which—

Figure 1 represents a front elevation of the machine embodying my invention. Fig. 2 is an end elevation of the same as viewed from the right of Fig. 1. Fig. 3 is an end elevation of the same as viewed from the left of Fig. 1. Fig. 4 is a vertical section of the same, taken as on line 4 4, Fig. 1, and as viewed from the left of said line. Fig. 5 is a detached rear view of the driving-shaft and its attachments, the shaft being shown as broken to economize space in drawing. Fig. 6 is a perspective view of a portion of the beam which guides the canvas or other material to which the reeds are glued and showing clearly the construction by which the lapping of one edge of the canvas over the other as they are guided onto the drum may be effected. Fig. 7 is a sectional detail taken as on line 7 7, Fig. 4, and as viewed from the right of said line. Fig. 8 is a sectional detail taken as on line 8 8, Fig. 4, and as viewed from above said line.

The machine thus illustrated is composed of a frame A, (see Fig. 1), in which is mounted

in suitable bearings a shaft B, which carries a large drum C. Below the drum there is extended across and attached to the frame a guide-beam of peculiar construction, one half 55 its length D and the other half D' being of unequal diameters, for a purpose which will be explained, and below this guide-beam is a rock-shaft E, carrying a series of tension-fingers F. Across the front of the frame, 60 above the drum, there is extended a rock-bar G, which carries two adjustable edge-rests H H', and through the side of the frame there is an adjustable sliding rod I, carrying an end gage I'. Above this bar G and parallel therewith a shaft J, secured in the sides of the frame, carries a series of rolls K K, the ends of which abut against each other and which are secured in place on the shaft by short sleeves L L, fastened by set-screws. Above 65 shaft J is a parallel rock-shaft M, secured in the sides of the frame and carrying a series of tuckers or curved fingers N, the shaft being actuated in one direction by two spiral springs P P' and in the opposite direction by a cam mechanism, which will be described. Above M is a parallel shaft Q, which carries a series of grooved pulleys R R', over which and around rolls K on shaft J are extended a corresponding number of weight- 70 ed steel bands S S. Referring now to Fig. 2, it will be seen that bands S pass from pulleys R to pulleys R', over which they are connected with an equal number of weights T, enclosed in a wooden casing T', open at its top 75 and bottom to allow of the movement of the weights to the extent required. These bands are attached at their opposite ends to drum C in a line across the face thereof at C' and pass thence over the periphery of the drum 80 to and under the rolls K to rolls R and R' and weights T. The drum C is counterbalanced by a weight attached to a rope U, which is secured to the drum at U' and passes around the periphery of the same, near one end thereof, and thence over suitable guide-rolls to any 85 convenient place that will afford room for the rise and fall of the weight as the drum is turned. On the low rear portion of the frame are mounted two rolls V V', upon which canvas is wound and indicated only by dotted lines W W' and from each of which the can- 90 95 100

vas is extended to drum C, passing under the guide-beam D D' (see Fig. 1) and up over the body of the drum to a set of hooks C², secured thereto and to which the ends of the 5 canvas drawn from rolls V V' are attached. The guide-beam D D' is formed as shown in Figs. 1 and 6, part D' being larger in diameter than D and eccentric thereto and having a lip D², which projects over D. This construction of the guides conveniently effects the overlapping of the two adjoining edges of the strips of canvas and is for that purpose only. The lip D² stands off from D, so as to allow one edge of the canvas to pass behind 10 it and be guided by the enlarged end of D', while the opposite strip of canvas passes over the outside of lip D² and against the flange on the same and is thereby guided to the drum over the edge of the adjoining canvas, thus 15 overlapping the same on the drum. When a simple abutting of the edges only is desired, the end fastening of the guide-beam may be loosened in the frame and the beam reversed or turned half around, so as to bring the straight 20 side of the beam which is opposite the lip D² around into the position of the lip, when by tightening the beam again in the frame and adjusting the distance apart of the outer edge-guides D³ and D⁴, so that it will equal 25 the combined width of the two strips of canvas, the adjustment will be complete to simply abut the edges as they are guided onto the drum. Thus the beam is adapted to abutting or overlapping the edges, as may be desired. 30 To keep the canvas smooth and even upon the drum while being wound thereon, the tension-fingers F upon rock-shaft E are employed. The fingers press upon the canvas as it passes between them and beam D by 35 force of a spiral spring F², shown in Fig. 2 as attached at one end to lever-arm F' and at its opposite end to the frame of the machine. This spring acts constantly by its contractile power to hold fingers F against the guide-beam D, thus placing a check upon the movement 40 of the intervening canvas, keeping the same under proper tension for the purposes stated. A lever E' is also secured to rock-shaft E and carries near its upper end a curved 45 catch E², which is pivoted to E' and overhangs a hub or boss E³ on the frame, which boss has a notch in its upper face into which a tooth on catch E² drops when arm E' is drawn forward against the force of the spring F² and 50 secures the lever in that position for the purpose of relieving the canvas from the pressure of the tension-fingers E when it is necessary or desirable to move the canvas free from the tension thereon. 55 Mounted in suitable bearings on the rear of the frame is the shaft X, which carries the pulley X', loosely mounted thereon and driven by belt X³, and the clutch mechanism X³, fixed upon the shaft and so constructed that a 60 clutch-pin actuated by a spring concealed in the hub of the clutch interlocks with the pulley, and thereby turns the shaft, except when 65

the pin is disengaged from the pulley, by means of the stopping and starting rod X⁴, which has a handle X⁵ pivoted thereto, as plainly shown in Figs. 2, 3, and 4. When the handle X⁵ is turned down to a horizontal position, as shown in solid lines in said figures, its inner end bears against the frame and draws forward the rod X⁴, to which it is pivoted and which is arranged to slide in the frame, as shown. A spring on the opposite end of the rod forces it back again when handle X⁵ is raised to the vertical position shown in broken lines. When the rod is drawn forward, as stated, it releases the spring-actuated clutch-pin, which instantly engages pulley X' and sets the shaft X in motion. When handle X⁵ is raised, as stated, it allows the rod to be retracted by force of its spring and to instantly disengage the clutch-pin from the pulley, and thus to stop the rotation of the shaft. No novelty is claimed for the clutch mechanism itself. The shaft X thus actuated sets in motion an eccentric Y, secured thereon, which, through its connecting-rod Y', operates the pawl-lever Z, and through it the gearing which turns drum C, as clearly shown in Fig. 4. This ratchet mechanism is secured to the side of the frame near the front of the machine and 95 comprises a hand-wheel Z', mounted on a short shaft Z²; a ratchet-wheel Z³, mounted on shaft Z²; an arm Z⁴, arranged to turn on a projection on frame A and carrying on its outer end a shield which projects over and across the teeth of the ratchet-wheel Z³; a lever Z, mounted on shaft Z² and carrying a pawl Z⁵, which engages the teeth of the ratchet-wheel Z³; a pinion Z⁶, mounted upon shaft Z², which engages a gear Z⁷, mounted on the drum-shaft B, and a pawl Z⁸, pivoted to the frame and arranged to engage the teeth of the ratchet-wheel and serve as a detent to prevent a reaction of the wheel under the pull of weights T, while the driving-pawl retracts to renew its hold thereon. Through this ratchet mechanism drum C is turned with an intermitting movement, the extent of which is regulated by the shield on arm Z⁴, which is interposed between the pawl and ratchet-teeth, so that the pawl during a part of its movement rides upon the shield and is thereby prevented from engaging the teeth, and thus the extent of the movement of the ratchet-wheel may be limited within the range of the pawl to one or more teeth. In practice the throw of the pawl covers four teeth; but it is sometimes necessary to vary the movement of the wheel for reasons which will be stated. 110

The regulation of the feed movement of the ratchet-wheel Z³ is effected by means of the lever-arm Z⁴, (see Figs. 4, 7, and 8,) which, as before stated, is arranged to turn on a projection on frame A and carries a shield Z⁹ between the teeth on the ratchet-wheel and the driving-pawl Z⁵. The arm Z⁴ is connected with a short rod Z¹⁰, which slides in frame A and at its outer end is pivoted to a handle-lever Z¹¹. On the rod is a spiral spring Z¹²,

one end of which bears against an inner face of the frame opposite the handle Z^{11} . By raising the handle to a horizontal position it draws the rod Z^{10} forward against the force of spring Z^{12} and at the same time swings the arm Z^4 on its bearing and carries its shield Z^9 farther into the range of the pawl Z^5 and covers the ratchet-teeth beneath it to a greater extent, thus preventing its engagement with the teeth covered and shortening its effective action and movement of the wheel. Dropping the handle Z^{11} into the position indicated in Fig. 4 allows the spring on rod Z^{10} to reverse the movement of the parts and allows the driving-pawl Z^5 to take more teeth and increase the feed movement in the manner before described. Upon the end of shaft X farthest from the driving-pulley there is fastened a cam Y^2 . A forked rod Y^3 works upon the shaft back of the cam and carries a roll which is in contact with the face of the cam, as shown in Fig. 3, while the long arm extends forward and upward and connects with a short arm Y^4 , which is attached to the shaft M , that carries the tuckers N . This cam Y^2 , acting through rod Y^3 on arm Y^4 , serves simply to open at the proper time the fingers or tuckers N by swinging them outward against the force of the springs $P P'$ on the shaft M , and said springs by reaction after a reed has been put in place to be acted upon turn the shaft M and carry the tuckers into action against the reed and force the same into place under bands S and against the next preceding reed. The cam Y^2 is so adjusted on shaft X relatively to the clutch action that when the clutch mechanism is operated to stop the machine the tuckers invariably stand open when the machine stops, and the feed ratchet-pawl also at such time rests upon the shield and out of contact with the teeth of the ratchet-wheel and ready for a forward movement when the clutch is released to start the machine again.

The customary method of producing the work for which this machine is designed is to cover a board or table with canvas of the dimension desired, apply the glue, place the reeds thereon, support the board upon a framework having bars arranged above and extending across the board over the reeds, and then secure the reeds upon the glued canvas by driving wedges between the cross-bars and tops of the reeds. When the glue has sufficiently dried, then the product of this comparatively slow and limited hand process is ready for whatever purpose it is designed.

The practical operation of my machine hereinbefore described is as follows: One or more rolls of canvas being mounted on the frame, as at V and V' , the ends are drawn to the front of the machine. One, as W , from roll V is passed upward between fingers F and beam D' to the drum C , to the circumference of which it is secured by hooks C^2 . Another strip of canvas W' from roll V' is passed in like manner under and over beam D and also

secured on the drum by other hooks C^2 . The inner edges of the canvas will be guided in the manner hereinbefore described, one passing over part D behind lip D^2 and the other over lip D^3 , so that the latter will overlap the former as they pass onto the drum C ; but when the beam D D' is turned half around, as has been described, said edges will abut against each other on the drum. When the canvas has been secured to the hooks C^2 on the drum, either with the edges lapped or abutted, and the tension-fingers F are permitted to act thereon, it is ready for the glue and to proceed with the attachment of the reeds. A coat of glue is now applied to the canvas with a brush in the usual manner and to such extent as may be deemed practical, additional glue being supplied from time to time as the work progresses and when required. Then the reeds, which are kept heated in an oven near at hand, are taken by the operator one by one and placed with one edge against the rests $H H'$ and one end against the gage I' , when, the machine having been started, the tuckers N swing down behind the reed and against its edge and press it forward upon the canvas on the revolving drum and under the bands S to the extent required, the bands pressing it by stress of their weight firmly into the glue as they move around with the drum carrying the canvas and reed to the extent of the feed movement, when the tuckers retreat and another reed is placed in position in like manner, which in turn is acted upon by the tuckers, which again return to their work and by a yielding spring-pressure force the reed home under the bands and into contact with the preceding one, and so on. If through slight variations in the reeds or from any other cause the ratchet-feed, moving to the extent of, say, four teeth, spaces the reeds too far apart, then the shield over the ratchet-wheel may be brought into use in the manner already described to prevent the actuating-pawl from taking so many teeth at one throw and reducing it to, say, three teeth. Thus the uniformity desired in spacing or compacting the reeds on the canvas may be obtained. This operation of covering the canvas with reeds may go on automatically and expeditiously after the reeds are presented to the machine, as stated, and with great accuracy and perfection until the circumference of the great drum is covered with the completed work, thus producing material enough for the construction of several roll-tops or other articles at one operation. The pressure-bands constitute a moving clamp which constantly exerts the needed pressure upon the reeds as they are successively introduced and throughout the progressive movement of the canvas. When the drum is thus fully covered or at any time when it may be desirable to remove the work therefrom, the canvas thus covered is severed from the uncovered portion, the bar G is turned to throw the edges of the rests $H H'$ upward out of the

path of the returning reeds H^2 , and the detent Z^8 being thrown out of engagement with the ratchet-wheel the drum is turned backward by means of hand-wheel Z , thus 5 winding therefrom the completed strip or body of combined cloth and wood after sufficient time has been allowed for the proper hardening of the glue. The machine having been thus cleared of its completed product is 10 again ready to proceed with a similar production in a like expeditious manner.

The weight on rope U counteracts the pull of weights T on bands S' and restrains the tendency of weights T to turn the drum too 15 rapidly when the work is being unwound and removed therefrom, thus relieving the work of the operator, who manipulates the hand-wheel at such time free from the check of the detent Z^8 .

20 The circumferential face of the drum serves as a supporting-table having a progressive movement, and the weighted bands S , attached thereto, serve as correspondingly-progressive clamps, holding the reeds under a 25 constant pressure to the glued face of the intervening canvas and as long as the operation continues.

25 The movable drum and bands and their mode of coöperation in accomplishing the 30 purposes of the machine are the most essential features of my invention.

I claim—

1. The combination of a drum for supporting the flexible material to which the reeds 35 are to be attached; mechanism having an adjustable movement for turning the drum intermittently on its axis; weighted bands attached to, moving with, and pressing upon the circumference of the drum; and a rock-shaft, and means for actuating the same, by which fingers are operated for pressing, with yielding pressure, the reeds successively between the bands and drum and onto the glued material, all substantially as specified.

45 2. The combination of a drum for supporting and moving the flexible material to which the reeds are to be attached; a ratchet movement for turning the drum intermittently on its axis; weighted bands arranged to press 50 upon the circumference of the drum and to move therewith; a rock-shaft carrying fingers for pressing the reeds successively between the bands and drum and onto the glued material; and mechanism for moving the rock-shaft so as to open, or retract, the fingers simultaneously with the retraction of the ratchet-pawl of the feed movement, all substantially as specified.

55 3. The combination with the drum and

means for turning the same on its axis, of the 60 guide-beam D arranged to be reversed, and constructed with an eccentric part D' , and a lip D^2 , and provided with adjustable outer edge-guides D^3 and D^4 , whereby it is adapted to either abut the adjoining edges of the material on the drum or to overlap them, as may be desired, all substantially as set forth.

4. In combination, drum C , mounted in frame A , upon shaft B : mechanism for turning the drum upon its shaft: guide-beam D , 70 secured to frame A , below the drum and arranged to direct the material to the drum: rock-shaft E , provided with an actuating-spring and tension-fingers, F , arranged to bear with the force of the spring against the 75 material passing over the guide-beam: shaft Q , secured in the frame above the drum and provided with grooved pulleys, R : a parallel shaft J , secured in frame A , below the top of the drum and provided with rolls K , corresponding in number to pulleys R : a corresponding number of bands, S , which pass over pulleys R , and under rolls K , and are provided with an equal number of weights T : and a counterweight attached to the drum 85 and arranged to counteract the weights on bands S , all substantially as and for the purposes specified.

5. The combination of drum C , mounted and operated substantially as described, with 90 pulleys R , arranged above the drum, on a shaft parallel therewith: rolls K , arranged below the top of the drum on a shaft parallel therewith: and a corresponding number of weighted bands passing over said pulleys and 95 under said rolls, and attached to the drum, whereby the bands are forced to bear upon the front face of the drum, at the proper height to receive the reeds, substantially as shown and described.

6. The combination with drum C , and the band-clamps, S , of the rock-shaft, M , provided with springs P , and fingers N , and actuated by the cam Y^2 , to open the fingers, and springs P , to close them upon the reeds, 105 substantially as described.

7. In combination with rock-shaft E , carrying the tension-fingers F , and provided with an arm F' , and actuating-spring F^2 , the handle-lever E' , provided with a catch E^2 , which 110 is arranged to interlock with the hub E^3 , to restrain the action of spring F^2 , and release the goods from the tension, as and for the purposes specified.
